UNITED STATES PATENT OFFICE.

GEORGE S. BLAKESLEE, DECEASED, LATE OF OAK PARK, ILLINOIS, BY GEORGE R. BLAKESLEE, EXECUTOR, OF OAK PARK, ILLINOIS, AND GEORGE P. ANSTISS, OF OAK PARK, ILLINOIS; SAID GEORGE S. BLAKESLEE AND GEORGE P. ANSTISS ASSIGNORS TO G. S. BLAKESLEE & CO., OF CICERO, ILLINOIS, A CORPORATION OF ILLINOIS.

PADDLE FOR WASHING MACHINES.

Original application filed August 2, 1923, Serial No. 655,241. Divided and this application filed March 28, 1925. Serial No. 19,020.

This invention relates to paddles or dashers for washing machines of the type of that illustrated and described in the pending application of George S. Blakeslee, filed 5 March 29, 1920, Serial No. 369,741, which has matured into Patent No. 1,591,506, the present application being divisional of our co-pending application Serial No. 655,241, filed 10 August 2, 1923, in which co-pending application there is also shown a washing machine of this general type. This invention has for its object to provide an improved paddle for use in such machines, which will enter the water smoothly and with least resistance, so 15 that it may be rotated at high speed with a comparatively small expenditure of power, and will take up the water and throw it in the form of a shower throughout the upper portion of a washing compartment, so that 20 it will impinge against the dishes or other articles contained therein with sufficient force to cleanse them properly. Such object is accomplished as illustrated in the drawings and hereinafter described. What we regard 25 as new is set forth in the claims.

In the drawings,—

Fig. 1 is a vertical sectional view of the improved paddle taken on line 1—1 of Fig. 2, illustrating particularly the means for securing said paddle on its supporting shaft;

Fig. 2 is a front view of said paddle, a portion of the supporting shaft therefor being shown in elevation;

Fig. 3 is a detail, being a section on line 35 3—3 of Fig. 1, the supporting shaft being omitted; and

Fig. 4 is also a detail, being a section on line 4—4 of Fig. 1.

Referring to the drawings,—5 indicates the supporting shaft on which the paddle or dasher is mounted. The paddle itself comprises two side plates 6, 7 each sectoral in form and provided with a straight leading edge portion 8 and two curved edge portions 45 10 and 11, said plates being suitably connected together near the margin of the trailing edge portion 11 by a curved bottom plate 12 interposed therebetween. The two side plates 6—7 and the curved bottom plate 12 50 are constructed as separate sheet metal stampings. In the preferred construction herein illustrated this curved bottom plate 12 is

welded to the side plates so as to make a watertight connection therewith, as shown at 13 in Fig. 4, but it is to be understood that 55 any other suitable means may be employed for securing the side plates to said curved plate. As will be seen, the side plates 6 and 7 are somewhat triangular in shape, the upper margins 8 thereof providing comparatively 60 sharp leading edges which enter the water easily and without disturbance, as is desirable not only because the paddle wheel may consequently be rotated at high speed with less expenditure of power, but also because 65 in washing machines of the type with which our improved paddle is particularly adapted to be used, only a small quantity of water is usually contained in the tank and, as a number of paddles are generally provided, arranged to dip successively into the water, it is 70 important that each paddle operate in such manner as not to interfere with the efficiency of the others. By providing the extended side plates, also, the paddle takes up a considerable amount of water, and distributes 75 it efficiently throughout the washing compartment. The extended side plates also function to laterally confine a body of water therebetween in advance of the bottom wall 80 12 striking such body of water, and thereby prevent or minimize side splash of the water. Such side splash is usually of little benefit for washing the articles in the machine, as it is only the water which is thrown radially by 85 the paddle that has the proper direction and sufficient velocity to perform the cleansing operation.

To provide means for securing the paddle on its supporting shaft the end of the curved 90 bottom plate 12 adjacent to the margins 8 of the side plates is turned back upon itself to form a loop 14 which clamps the shaft 5, and an overlapping end portion or lip 15 thereof, which is bent to conform to the curvature of 95 the main body portion of the plate 12, and is secured to the main body portion by bolts 16 which pass therethrough, and nuts 17 screwed on said bolts. Thus the loop 14 may be clamped tightly down upon the shaft 5, thereby securing the paddle firmly in position on said shaft with the inner end of the bottom plate 12 in tangential relation thereto. 100 It will be understood, of course, that the side

plates 6, 7 are provided with suitable holes therein for the passage of the supporting shaft therethrough.

To guard against the paddle becoming loose on said supporting shaft 5 because of the nuts 17 working loose, further securing means is provided comprising an internally threaded collar 18, which is securely connected to the loop 14 by welding, or in any other suitable manner, and a set screw 19 which passes through said collar and is adapted to engage with the shaft 5, as shown in Fig. 1. It is obvious, of course, that the paddle may readily be removed, or adjusted on the shaft as desired, by loosening the nuts 17 and the set screw 19.

By constructing the paddle in the manner described, a plurality of such paddles may be mounted upon a supporting shaft at any desired distance apart, and in any desired angular relation to each other, and will enter the water smoothly and easily without much resistance or disturbance of the water, so that all the paddles will operate efficiently, and the paddle wheel as a whole may be economically operated at high speed. Owing to the wide side plates 6 and 7, the paddles will take up a considerable quantity of water, and by centrifugal force will distribute it generally throughout the upper portion of the washing compartment, so that the interior of such compartment will be filled with flying particles of water which will thoroughly wash and scour the dishes or other articles therein.

What we claim as the invention of said GEORGE S. BLAKESLEE, deceased, and GEORGE P. ANSTISS, and desire to secure by Letters Patent, is—

1. A paddle for washing machines comprising approximately triangular plates spaced apart and having a straight edge 8 and a long curved edge 10 subtending substantially a right angle, and a curved bottom

plate connecting said first mentioned plates together near the other edge thereof.

45

2. A washing machine paddle constructed of two spaced side plates and a curved bottom plate extending therebetween, each of said side plates being of sectoral form and having its leading and trailing edges extending substantially at right angles to each other, the lateral edges of said bottom plate being welded to said side plates adjacent to their trailing edges, a loop formed in the inner end of said bottom plate to form a hub for mounting the paddle on a shaft, said side plates having holes therein in alinement with said loop for receiving said shaft, and means for clamping said loop on the shaft.

50

55

3. A washing machine paddle constructed of three sheet metal stampings consisting of two spaced side plates and a curved bottom plate extending therebetween, each of said side plates being of sectoral form and having its leading and trailing edges extending substantially at right angles to each other, the lateral edges of said bottom plate being secured to said side plates adjacent to their trailing edges, and a loop formed in the inner end of said bottom plate to provide a hub for mounting the paddle on a shaft.

60

65

70

4. A washing machine paddle comprising two spaced side walls and a curved bottom wall, each of said side walls being of sectoral form and having its leading and trailing edges subtending substantially a right angle therebetween, whereby said side walls laterally confine a body of water therebetween in advance of the bottom wall striking the same and thereby prevent side splash of the water.
